PORTABLE SWAGING TOOL

Clayton L. Solum, Monterey Park, Calif., assignor to
Northrop Aircraft, Inc., Hawthorne, Calif., a corpora-
tion of California

Application March 5, 1956, Serial No. 40,468

Term of patent 14 years

(Cl. D54—13)

Fig. 1

Fig. 2

Fig. 3

Fig. 4

Fig. 5

Figure 1 is a side elevation view of the portable swaging tool showing my new design.

Figure 2 is a top plan view of the portable swaging tool shown in Figure 1.

Figure 3 is a left end view of the portable swaging tool shown in Figures 1 and 2.

Figure 4 is a right end view of the portable swaging tool shown in Figures 1 and 2.

Figure 5 is a three-quarter view in perspective of the portable swaging tool of Figures 1 and 2, rotated end for end.

I claim:

The ornamental design for a portable swaging tool, substantially as shown.
